PROJECTILE.

1,112,413.

Specification of Letters Patent. Patented Sept. 29, 1914.

Application filed December 24, 1913. Serial No. 808,538.

To all whom it may concern:

Be it known that I, FRANK O. HOAGLAND, a citizen of the United States, residing in Bridgeport, in the county of Fairfield and State of Connecticut, have invented certain new and useful Improvements in Projectiles, of which the following is a specification.

This invention relates to that class of elongated projectiles in which a soft-metal core is protected by a point-cap or jacket-tip applied thereon, either with or without being accompanied by a body casing or jacket for the rearward part of the core; and the present improvements have for their object to furnish a simple and effective means whereby the point-cap or covering member may be held in position on the core without requiring any portion of such cap or member to be turned or indented inwardly so as to take into the core, as when using an inwardly turned flange or inwardly-extending projections formed by exteriorly indenting the wall of the point-cap or analogous core-covering member.

In the accompanying drawing, forming a part of this specification, Figure 1 is a side elevation of a projectile made in accordance with my present improvements, and showing the projectile provided with a main core case H extending forwardly (toward the right hand) to about midway of the point-portion of the core, and with a point-cap or jacket-tip, P, secured on the point of the core. Fig. 1^a is a view of the point-cap, P, in the same position as illustrated in Fig. 1 but shown in section. Fig. 2 is a longitudinal sectional view of the projectile as seen from below in Fig. 1. Fig. 2^a is a transverse section through the projectile in the line Z—Z, Fig. 2, showing the parts on the left-hand of said line as seen from a position at the right-hand thereof. Fig. 3 illustrates a slightly modified arrangement of the body casing or jacket relatively to the point-cap and core of the projectile, some portions of this view being broken away for more clearly showing the details of the construction. Fig. 3^a is an end view of the form of projectile shown in Fig. 3, as seen from the right hand in said figure. Figs. 4, 5 and 6 illustrate further variations in the arrangement of the point-cap relatively to other parts of the projectile.

Similar characters represent like parts in all of the views.

The point-cap, which is designated in a general way by P, is adapted for use on expendable projectiles of the so called "mushroom" class, and for use in connection with a main core-casing or body-jacket, as H, arranged to cover the body as well as a part of the point portion of the core, and arranged with its forward edge 2 close to the rearward edge 3 of the point-cap, as in Figs. 1 and 2; or with an intervening space, 9, between said forward edge 4 and said rearward edge 3 of the point cap, P, as in Fig. 3;—or, with the forward edge 2 of the jacket underlying the rearward edge 3 of the point cap, as in Fig. 4.

In practice, the core may be made and finished in various ways, among which are casting and swaging. When the point-cap is provided with the openings, 5, whether these be circular (as heretofore shown), elliptical or polygonal in outline,—or of other suitable shape, not shown,—the core metal may have extending therefrom one or more projections, as 7, for filling said openings and thereby locking the point-cap in place upon the point portion c' of the core C. When the core is formed by casting the metal into the point-cap,—this being done by means of a suitable mold,—the molten metal may thus be run out into said openings 5, and thereby fill the same and make the outside of the finished projectile of a smooth and regular form. In those cases in which the core is formed in a well-known manner by a swaging operation, similar outwardly extending parts of the core may be formed within said openings 5 by the method of extrusion, or flowage. It will, of course, be understood that in any given instance such operations as here referred to may be varied in different ways according to the custom of such metal-working arts and within the scope and limits of the improvement herein illustrated and described.

From a comparison of the several views as herein described,—especially the sectional portions of Figs. 2, 3, 4 and 5,—it will now be evident that the functions and mode of action, and also the advantages, of the described cap-retaining core-projections are substantially the same in each of the arrangements illustrated, and whether those projections are one, two or three in number. When it is desired for any reason to restrict the area of the exposed core-metal

surface, it is, of course, only necessary to reduce accordingly the diameter of the openings 5 in the cap P, and then to make such a number of openings as may be suitable for the requirements in any given instance. For general use, however, I deem it sufficient to make two of the openings, 5, 5, in the cap, as in Figs. 1 to 2^a, inclusive; but as a comparative illustration I have indicated three 10 of the openings in the cap-member as shown in Figs. 3 to 5 inclusive. Instead of making the core-projections by the method of casting or by the method of extrusion, these projections may, if desired, be provided by the 15 method of insertion. This method is indicated in Fig. 6 where the core-covering member, or jacket member, P, has two openings, at 5, 5, as in Fig. 1 to Fig. 2^a, and the core C has a transverse opening or perforation, in which a plug, as 12, is inserted, so that the ends 7, 7, of such insertion fill the openings in the member P, and so form a smooth exterior for the projectile where the cover-perforations are located. In practice 20 the inserted projections 7 may be made of a soft metal, similar to that used for the core C; or, said parts may be made of a slightly harder substance or metal; the proportionate dimensions may also be varied. While 25 the present improvements are shown applied to projectiles having greatly elongated point-portions, as from x to y, Fig. 1, the described cap-retaining means are obviously applicable to such core coverings of 30 widely varying proportions.

In Fig. 6, the extreme tip portion of the point-cap P is omitted, leaving a forward edge, as at a, while the extreme point, t, of the core-point, C', is shown rounded over, 35 and it will be evident that this or a similar point formation may be adopted for the arrangements as otherwise shown in Figs. 1, 2, 3, 4, and 5, without affecting the character of the retaining projections 7, or their relations to the other details of the projectile.

Having thus described my improved projectile, I claim:—

1. In a projectile for small arms, a soft-metal core comprising an elongated core-point, in combination with an unflanged point-cap without indentations for taking into the core-point, and having one or more openings therein, and cap-retaining projections extending outwardly from the core into said openings, whereby to lock together the core and point-cap, substantially as described.

2. In a mushroom projectile for small arms, a soft metal core comprising an elongated core-point, in combination with a point-cap having one or more openings therein, and cap-retaining projections integral with the core and extending outwardly into and filling said openings, whereby to interlock the core and point-cap, and provide a smooth exterior for the capped point-portion of the projectile.

3. In a mushroom projectile or bullet of the class described, comprising an elongated core-point, in combination with a covering member applied to the core and having a plurality of openings therein, and cap-retaining projections extending outwardly from the core and filling said openings in the covering member, substantially as described.

4. A mushroom bullet comprising a soft metal core, a jacket-body and a jacket-tip, the said tip being superficially applied to the pointed end of the soft metal core and formed with one or more openings into which the metal of the core exudes to form a lock or locks for maintaining the tip in engagement with the core without being set inward and embedded therein.

FRANK O. HOAGLAND.
